US0D1052943S

(12) **United States Design Patent** (10) **Patent No.:** **US D1,052,943 S**
(45) **Date of Patent:** **** Dec. 3, 2024**

(54) **FOLDABLE CHAIR FRAME**

(71) Applicant: **JKL CORPORATION**, Seoul (KR)

(72) Inventor: **Jeh Kun Lah**, Seoul (KR)

(**) Term: **15 Years**

(21) Appl. No.: **35/519,272**

(22) Filed: **Nov. 15, 2023**

(80) **Hague Agreement Data**

Int. Filing Date: **Nov. 15, 2023**

Int. Reg. No.: **DM/233417**

Int. Reg. Date: **Nov. 15, 2023**

Int. Reg. Pub. Date: **Dec. 8, 2023**

(30) **Foreign Application Priority Data**

Jun. 2, 2023 (KR) 30-2023-0021311

Primary Examiner — Paul D Bohannon

(57) **CLAIM**

The ornamental design for a foldable chair frame as shown and described.

DESCRIPTION

1.1 : Perspective

1.2 : Front

1.3 : Back

1.4 : Left

1.5 : Right

1.6 : Top

1.7 : Bottom

1. Title of the design: Foldable chair frame; 2. Use of the design: used in combination with a fabric seat; 3. Distinctive points: shape of the product as shown; 4. View best showing the design: Fig. 1.1.

1 Claim, 7 Drawing Sheets
